UNITED STATES PATENT OFFICE.

FRANK W. THEODORE KLAUSING, OF LAKEWOOD, AND WILLOUGHBY C. TACKABERRY,
OF CLEVELAND, OHIO.

TOGGLE-LOCKING FOLLOWER-HOLDER.

1,240,223.

Specification of Letters Patent. Patented Sept. 18, 1917.

Application filed October 22, 1915. Serial No. 57,370.

To all whom it may concern:

Be it known that we, FRANK W. THEODORE KLAUSING and WILLOUGHBY C. TACKABERRY, both citizens of the United States, residing, respectively, at 1539 Lauderdale avenue, Lakewood, Ohio, and 7312 Clinton street, Cleveland, Ohio, both in the county of Cuyahoga, have invented new and useful Improvements in Toggle-Locking Follower-Holders, for Use with Trunks and other Wardrobes, of which the following is a specification.

Our invention relates to holders for the clothes or other contents of trunks or other wardrobes, and particularly relates to efficient means for locking a follower or frame against the clothes so as to retain the same rigidly and yet conveniently allow for the varying amount of contents of the trunk at different periods.

The annexed drawing and the following description set forth in detail certain means embodying our invention, the disclosed means, however, constituting but one of various mechanical forms in which the principle of the invention may be employed.

In said annexed drawing:—

Figure No. 1 shows a boss plate of any suitable metal, a pair of which are intended 30 to be affixed to the opposite inside walls of a trunk or other wardrobe; Fig. No. 2 represents a notched plate of any suitable metal intended to be complementary to and fit upon the boss plate and provided with guiding grooves hereinafter more fully described; Fig. No. 3 represents the two plates assembled, showing the locked and unlocked positions and the actuating toggle locking member; Fig. No. 4 represents an 40 end view; and Fig. No. 5 shows the toggle locking follower holder in position in a wardrobe trunk of ordinary design.

Referring to the annexed drawing, the boss plate is provided with a top flange *e*, 45 said plate being adapted to be attached to the inside wall of a trunk by pins *i*, so that said flange extends inwardly. A complementary movable plate provided with an inwardly extending and upwardly extending 50 flange in which are formed notches and teeth *b* is adapted to be movable with reference to the boss-plate to which it is attached by means of the pins *a* fixed to said boss-plate and adapted to register with the 55 grooves *c*, *d*, formed in the complementary

plate, as can be plainly seen in Fig. No. 2. There are a plurality of these teeth *b* and locking means is intended to be supported therein upon a pair of the complementary plates, such locking means being a rod *k*, 60 Fig. No. 5, for instance. The actuation of the complementary sliding plate and the consequent locking of the clothes or other trunk contents through the medium of the rod *k*, is effected by a toggle locking member, the elements of the same comprising a link *h* thereof consisting of a straight portion and a curved handle, and a second straight link *g*, the latter being pivoted to the sliding plate and to the first-named link 70 by pins *f*, said first-named link being also pivoted upon the front pin *a* connecting the boss and complementary plates. It is evident from the above description and the accompanying drawing that the actuation of 75 the handle *h* will effect the forward and backward movement of the complementary sliding plate through the medium of the aforementioned connections, the toggle locking member and the grooves *c* and *d*.

Our improved holder is intended to be used in pairs, as before mentioned, and the adjustable rod *k* is intended to bear upon or release any conventional clothes holder, such as the frame 1. 80

Our improved device provides simple means for the purposes stated, is very effective, located conveniently in the wardrobe with reference to its contents, and very adjustable as to the amount of said contents. 90

What we claim is:—

1. In a toggle-locking follower holder, the combination of a fixed plate; a complementary plate movable relatively thereto; a guide in said latter plate; a pin secured to 95 said fixed plate and adapted to register with said guide; a toggle-locking member pivoted to said movable plate and to said pin; and holding means supported by said movable plate. 100

2. In a toggle-locking follower holder, the combination of a plate intended to be affixed to the inside of a trunk or other wardrobe; a complementary plate provided with guiding grooves; pins affixed to said 105 first-named plate and adapted to register with said grooves; holding means actuated by said complementary plate; a link provided with a handle and pivoted to one of said pins; and a second link pivoted to said 110

complementary plate and to said first-named link.

3. In a toggle-locking follower holder, the combination of a pair of plates intended to be affixed to the opposite inside walls of a trunk or other wardrobe; a pair of complementary plates provided with guiding means; means, such as pins, affixed to said first-named plates and adapted to register with said guiding means, respectively;

holding means adjustably supported by said complementary plates; and toggle-locking means pivoted to said complementary plates and to said pins.

F. W. THEODORE KLAUSING.
WILLOUGHBY C. TACKABERRY.
